UNITED STATES PATENT OFFICE.

THOMAS S. HOMANS, OF BROOKLYN, NEW YORK, ASSIGNOR TO INTERTYPE CORPORATION, OF BROOKLYN, NEW YORK, A CORPORATION OF NEW YORK.

TYPGRAPHICAL MACHINE.

1,426,194.

Specification of Letters Patent. Patented Aug. 15, 1922.

Application filed October 19, 1921. Serial No. 508,684.

To all whom it may concern:

Be it known that I, THOMAS S. HOMANS, a citizen of the United States, residing at Brooklyn, in the county of Kings and State 5 of New York, have invented new and useful Improvements in Typographical Machines, of which the following is a specification.

The present invention relates to improvements in typographical machines and more 10 particularly to those of the linotype class substantially as shown and described in U. S. Letters Patent to O. Mergenthaler, No. 436,532, granted September 16, 1890.

Typographical machines of the kind referred to have heretofore been constructed generally to produce type bars or slugs having a maximum length of five inches and while many attempts have been made to substantially increase the length of type bars 20 obtainable from such machines and to thus increase the efficiency and broaden the range of use of the machine, such attempts have been unsuccessful, although developments have been made with this object in view 25 which enabled type bars or slugs to be obtained which were about one inch longer than those usually obtainable, but which did not materially increase the range of use of the machine.

30 The primary object of the present invention is to provide certain improvements which substantially increase the efficiency and broaden the range of use of typographical machines of the linotype class by 35 enabling such machines to produce type bars or slugs having a length of seven inches or a length equivalent to 42 ems, these improvements enabling machines of the linotype class to accomplish this result without re- 40 quiring changes in the machine other than those necessary to increase the capacity of the assembling and distributing mechanisms to accommodate the increased length of the lines. The improvements which enable 45 these results to be attained, pertain to the means which transfers the lines of matrices of increased length from the so-called first elevator to the so-called second elevator and the casting mechanism which according to 50 the present invention has an increased capacity which enables it to successfully cast the type bars or slugs of increased length from the lines of matrices, the casting mechanism in its preferred embodiment being 55 provided with means to control its capacity whereby it may cast type bars or slugs of

the usual or shorter lengths, as well as those of increased length.

To these and other ends, the invention consists in certain improvements and combinations and arrangements of parts, all as will be hereinafter more fully described, the features of novelty being pointed out particularly in the claims at the end of the specification. 65

In the accompanying drawings:—

Figure 1 is a front elevation of that portion of a machine of the linotype class which effects the transfer of the line of matrices from the first elevator to the second elevator, the line transfer means, as shown, being in accordance with the present invention; 70

Figure 2 is a detail perspective view of the line transfer means shown in Figure 1; 75

Figure 3 represents a transverse section through the line transfer means shown in Figures 1 and 2;

Figure 4 is a perspective view of casting mechanism constructed in accordance with 80 the present invention; and

Figure 5 is a top plan view of the metal pot illustrating how a cast may be made from a relatively short line of matrices.

Similar parts are designated by the same 85 reference characters in the several views.

The present invention is applicable generally to line casting machines of the kind wherein the line of matrices from which the type bar or slug is to be cast is presented 90 to the casting mechanism by an elevator or similar means, and after the cast has been made the line of matrices is transferred from such elevator to another or second elevator or equivalent means which conveys the matrices to matrix-distributing mechanism by which the matrices composing the line are returned to their respective cells or channels in a matrix storage magazine. The invention is particularly applicable to typographical machines of the linotype class, as is shown and described substantially in the Mergenthaler patent hereinbefore referred to, and the invention is so illustrated in the accompanying drawings and will be hereinafter described. It is to be understood 100 that the invention is not restricted to the precise construction shown, as equivalent constructions are contemplated and these will be included within the scope of the 105 claims.

In the present instance, 1 designates a

portion of a machine of the linotype class adjacent to the point of transfer of the line of matrices from the usual first elevator, after a cast has been made therefrom, to the 5 second elevator which conveys the line of matrices to the distributor, 2 designating the upper portion of the second elevator in position to receive the line of matrices M endwise from the channel in the first elevator, 10 it being understood that the line of matrices is elevated to the transfer point or to the level occupied by the second elevator 2 by the usual upward movement of the first elevator following the casting operation. The transfer 15 of the line from the first to the second elevator is usually effected by a line transfer carriage 3 which slides or reciprocates in a relatively fixed guide 4, the carriage carrying a finger 5 which is adapted to occupy a 20 position beyond the left-hand end of the line when the line is brought to the transfer level, as is shown in Figure 1, following which the line transfer carriage and with it the finger 5 are shifted toward the right in 25 Figure 1, the finger 5 thus coming against the end of the line and shifting the latter endwise onto the second elevator 2. The line transfer carriage in machines of the linotype class is reciprocated at appropriate 30 intervals and through a predetermined stroke by an arm or lever 6 which has a fixed throw and is usually actuated by a cam on the main or cam shaft of the machine. It is usual in machines of the linotype class to 35 connect the arm or lever 6 to the line transfer carriage directly by a connecting link or pitman.

In order to accommodate the line transfer mechanism to handle lines of matrices of 40 greatly increased length, as is contemplated by the present invention, it became necessary to increase the length of stroke of the line transfer carriage and in order to obtain this result within the limited space 45 available and to thus avoid reconstruction of this part of the machine, it became necessary to devise means to increase the length of stroke of the line transfer carriage without altering the timing and which means is compact so that it will perform its function and yet avoid interference with other adjacent parts of the machine. Preferably and as shown in the present instance, such means 50 comprises a toothed rack 7 which is fixed to the adjacent stationary part 1 of the machine in parallelism with and below the line of travel of the line transfer carriage 3, a toothed rack 8 which is fixed to or carried by the line transfer carriage and is parallel 55 to but offset forwardly relatively to the stationary rack 7, and a rolling or shifting gear member comprising a gear 9 which meshes with and traverses the stationary rack 7 and a gear 10 of proportionately smaller 60 diameter which meshes with and traverses the

rack 8 attached to the carriage. These gears 9 and 10 are fixed to one another so that they will rotate in unison and they are operatively connected to a stud 11 which latter is fixed or otherwise operatively connected to one 70 end of a link or rod 12, the opposite end of the latter being operatively connected to the usual actuating arm or crank 6. Preferably, a circular disk 13 is fixed to one side of the gear 9, the periphery of this disk coinciding with the pitch line of this gear and a cooperative rail 14 is fixed at one side of the rack 7, the upper edge of the rail being on the level with the pitch line of the rack. By this arrangement, the disk 13 and rail 14 80 will support the gear element during its to-and-fro movements under the action of the arm 6 and link 12 and will prevent bottoming of the teeth of the gear 9 and rack 7. A guard 15 is preferably applied to the forward side of the rack 7 and rail 14, this guard protecting the rack and its cooperating gear and also serving as a guide for the forward side of the disk 13, the rear side of this disk being engaged and guided by the 90 teeth of the rack 7 which project above its upper edge. The rack 8 attached to the line transfer carriage may, as shown, be formed by an overhang from such carriage, the overhang being preferably utilized as a guard 95 which encloses and accommodates the tops of the gear 9 and the disk 13.

It is to be understood that the ratio between the diameters of the gears 9 and 10 is such that the range of stroke obtained by 100 the usual line transfer operating arm or crank 6 is multiplied or increased as it is transmitted to the line transfer carriage, and hence the length of stroke of the line transfer carriage will be increased to the extent necessary to enable it to receive the line of matrices of increased length in front of the finger 5 and to shift through a range sufficient to completely transfer such line of matrices from the first elevator to the second elevator. The construction described enables this result to be attained without disturbing the actuating arm or crank 6 or its cam and, moreover, the mechanism is compact and is easily accommodated within the 110 limited space available in rear of the first elevator, when the latter is raised to its upper or line discharging position.

The casting mechanism commonly employed in line casting machines of the linotype class embody a mold and metal pot 120 which are constructed to produce type bars or slugs of relatively short length only, five inches being the limit of length heretofore used generally. The present invention provides casting mechanism which is capable of casting type bars or slugs of the substantially increased length and in its preferred construction it is capable of being easily and quickly adjusted to cast either the relatively 125 130

long type bars or slugs or the relatively shorter length commonly used. As shown in the present instance, 16 represents the mold which may be of the type generally used in machines of this class, it being understood that the length of the mold cavity is set or adjusted according to the length of the type bar or slug to be produced. In Figure 5 a line of matrices M' of the usual length is shown presented to one side of the mold, the line of matrices being clamped or locked between the usual vise jaws 17, and the metal pot 18 is presented to the opposite side of the mold and operates in a manner to be hereinafter described to cast the type bar in the mold. According to the present invention, the mouth piece 19 of the metal pot, which mouth piece is adapted to fit against the line of matrices from which the cast is to be made is increased in width to conform with the increased length of the lines of matrices which may be presented thereto for the casting of type bars or slugs of the increased length, the mouth-piece having preferably a row of suitably spaced openings 20 through which the metal is injected into the mold cavity and these openings in the mouth-piece are supplied with molten type metal by a pair of throats 21 and 22 which, as shown in Figure 5, are out of communication with one another; in other words, they independently supply type metal to respective portions of the mouth-piece. The throats 21 and 22 lead from individual pump wells 23 and 24 which may receive metal in the usual way from the main molten metal well 25 of the pot and they are fitted with individual pump plungers which are connected respectively to the plunger rods 26 and 27, it being understood that in line casting machines of the linotype class each downward stroke of the plunger of the metal pot serves to inject a supply of molten type metal through the mouth-piece of the metal pot into the mold to make the cast therein, although the metal pots commonly used in machines of the linotype class employed one plunger only, whereas, according to the present invention, two plungers are provided which supply type metal to different portions of the mouth-piece. I have found from experience that this double means for delivering metal to the mouth-piece is necessary, in order to enable the same casting mechanism to successfully cast either the long type bars or type bars of the relatively short lengths as commonly used, because if a single metal delivery means were provided for a mouth-piece designed to cast the relatively long type bars and it were attempted to use the same metal injecting means in the casting of type bars of the relatively shorter lengths, the metal delivered from a well and plunger adapted to the casting of long lines would leak between the mouth-piece and the matrices and vise jaws, due to the excess metal that would be injected, and this leakage presented a serious objection. By supplying metal from two wells and plungers, however, for the casting of the relatively long lines and rendering one of the wells and plungers inoperative so that the metal is supplied from only one well and plunger for the casting of the relatively short type bars, the injection of excess metal is avoided and the objections which presented themselves were overcome. The present invention provides means whereby the casting mechanism may be quickly and easily set for the casting of either the longer or shorter lines, it embodying preferably means for setting one of the plungers either into or out of operation according to the length of line being handled by the machine, thus enabling the casting mechanism to operate with equal facility, irrespective of the length of line being handled. As shown in Figure 4, the metal injecting plungers 26 and 27 are operatively connected to levers 28 and 29 which latter are pivoted at 30 to a stationary part 31 of the frame of the machine, and springs 32 and 33 act on the respective levers to force the plungers connected thereto downwardly to perform a metal-injecting operation. One of the levers, the lever 28 in the present instance, carries a roller 34 which travels on a cam 35, this plunger-actuating mechanism shown in the present instance corresponding substantially with that fully shown and described in U. S. Letters Patent No. 1,108,804, granted August 25, 1914, it being understood that a metal-injecting operation occurs at the proper period during each cycle of operations of the machine. By the construction described, the plunger connected to the lever 28 will perform a metal-injecting operation during each operation of the cam 35. Means is provided by which the other plunger connected to the lever 29 may be either set to operate in unison with the first-mentioned plunger, or it may be restrained from operation or otherwise rendered inoperative. Preferably and as shown, the lever 28 is provided with a step or lug 36 arranged below the lever 29 and this lever 29 may rest on this step or lug, in which case it will operate under the action of its spring 33 in unison with the other plunger, and hence metal will be injected by both plungers through the metal pot mouth-piece, this being the operation when the relatively long type bars are being produced. Suitable means is provided for restraining or preventing operation of the plunger connected to the plunger bar 27 so that one plunger only will operate during the projection of the relatively short type bars. As shown in the present instance, a hook 37 is

1 pivotally hung from a pin 38 and the lever 29 has a pin 39 fixed thereto, the hook 37 being adapted to engage beneath the pin 39 when the lever 29 is elevated and to thus restrain operation of the plunger connected to this lever. Suitable means is provided for setting or controlling the hook 37, a bar 40 being operatively connected to it in the present instance, this bar extending toward the front of the machine where it is provided with a suitable handle 41 and by pushing the bar 40 rearwardly the hook 37 will clear the pin 39 so that the plunger attached to the lever 29 may operate in unison with the plunger attached to the lever 28, whereby pulling the bar 40 forwardly after the lever 29 has been elevated by the cam 35, the hook 37 will engage beneath the pin 39 and will lock the lever 29 in elevated position and thereby preventing operation of the plunger attached to this lever. Any suitable means may be employed for holding the bar 40 in either of its two positions, a relatively fixed pin or projection 42 being provided in the present instance which is adapted to engage either one of the two notches 43 formed in the bar 40, these notches corresponding to the forward and rearward positions of the bar.

30 By constructing the casting mechanism as described, the proper quantity of molten type metal will be injected into the mold to fill it, when the relatively long type bars are being produced, owing to the conjoint operation of both metal-injecting plungers, and when relatively short type bars are being cast, the correspondingly short matrix lines M' and mold cavity are presented at one side of the metal pot mouth-piece, substantially as is illustrated in Figure 5, the relatively short mold cavity receiving the proper amount of molten type metal from one plunger through the single throat 21 which is divided off from the companion throat 32 throughout its length and as far as the discharge side of the mouth-piece, and hence escape of molten metal beyond the end of the line of matrices is avoided.

I claim as my invention:—

50 1. In a typographical machine having a line-transfer carriage and a reciprocatory actuating member therefor, means for enabling said carriage to advance lines of matrices of a length greater than the usual length, comprising motion-transmitting means operatively connecting such carriage and actuating member and operative to reciprocate the carriage through a range greater than the range of reciprocation of the actuating member.

2. In a typographical machine, the combination with a line transfer carriage and a reciprocatory actuating member therefor, of means for enabling said carriage to transfer lines of matrices of a length differing

from the usual length, comprising motion-transmitting means connecting said carriage and member and operative to vary the ratio of movement of the carriage relatively to its actuating member.

70

3. In a typographical machine, the combination with a line transfer carriage and a reciprocatory actuating member therefor including a reciprocatory link, of means for enabling said carriage to transfer lines of matrices of a length greater than the usual length, comprising motion-transmitting means between said link and the carriage and operative to cause reciprocation of the carriage through a range greater than the range of reciprocation of the link.

4. In a typographical machine, the combination of a line-transfer carriage, a reciprocatory actuating member therefor, and means for enabling said carriage to transfer lines of matrices of a length differing from the usual length, comprising an intermediate connection between said member and carriage operative to transmit motion at a ratio which will cause reciprocation of the carriage through a range different from the range of movement of the actuating member.

85

5. In a typographical machine, the combination of a line-transfer carriage, a reciprocatory actuating member therefor, and means for enabling the carriage to transfer lines of matrices of a length greater than the usual length, comprising a motion-transmitting device connected to said member to reciprocate therewith and having a motion-increasing connection with the carriage.

95

6. In a typographical machine, means for transferring lines of matrices of a length differing from the usual length comprising, in combination, a line-transfer carriage having a toothed rack connected thereto, another rack, a reciprocatory actuating member, and a gear element comprising gears of different ratios cooperating respectively with said racks.

100

7. In a typographical machine, a metal pot having a plurality of pumps, channels for the delivery of molten metal therefrom to the type casting molds, and means for cutting off the delivery of metal from one of said pumps.

115

8. In a typographical machine, a metal pot having a plurality of channels for the delivery of molten metal to the type casting mold, metal injecting means individual to each of said channels, and means for controlling the metal injecting means whereby one of said means may operate independently or a plurality of such means may operate concurrently.

120

9. In a typographical machine, a metal pot having a pair of channels for the delivery of molten metal to the type casting

125

130

mold, a pair of metal-injecting plungers for the respective channels, actuating means common to both plungers, means operative with one of said plungers to cause concurrent operation of the other plunger, and means for restraining the first-mentioned plunger from operation during operation of the latter-mentioned plunger.

In testimony whereof I have hereunto set my hand in presence of two subscribing witnesses.
